Primary Examiner — Eric Goodman*Assistant Examiner* — Amy Wierenga*(74) Attorney, Agent, or Firm* — Boyle Fredrickson, S.C.(57) **CLAIM**

The ornamental design for a triangular shaped preform, as shown and described.

DESCRIPTION

FIG. 1 is a cross section view of a circular preform with a triangular shaped cross sectional area;

FIG. 2 is a cross section view taken along lines 2-2 in FIG. 3, of a circular preform with a triangular shaped cross sectional area, shown in use; and,

FIG. 3 is a perspective view of the circular preform with a triangular shaped cross sectional area according to FIGS. 1 and 2.

The broken lines shown in the drawings depict portions of the article that form no part of the claimed design.

1 Claim, 3 Drawing Sheets
